UNITED STATES PATENT OFFICE.

GEORGE H. REYNOLDS AND THOMAS J. RIDER, OF NEW YORK, N. Y.

VALVE-GEAR FOR DIRECT-ACTING ENGINES.

SPECIFICATION forming part of Letters Patent No. 247,997, dated October 4, 1881.

Application filed July 5, 1881. (No model.)

To all whom it may concern:

Be it known that we, GEORGE H. REYNOLDS and THOMAS J. RIDER, both of the city and county of New York, in the State of New York, have invented certain new and useful Improvements in Valve-Gear for Direct-Acting Engines, of which the following is a specification.

Our invention relates to direct-acting engines, such as are embodied in steam-pumps, but which may be applied to other purposes, and in which the auxiliary valve is turned partly round or oscillated at each stroke of the piston to admit steam to operate the main valve. An example of such an engine and valve-gear is shown in our Letters Patent numbered 237,323, and dated February 1, 1881. In the engine represented in said patent, and in other engines of the same class, the valve-rod is turned or oscillated by means of an arm projecting from the piston-rod and acting upon inclines upon the valve-rod, or on a yoke or bar attached thereto near each end of the piston's stroke.

The object of the present invention is to obviate an objection which is found in practice to exist in the construction of the parts as represented in the aforesaid Letters Patent, consisting in the cutting of grooves in the valve-operating arm by its working during a portion of its stroke on the edge of the yoke, and also to enable the inclines and the parts which act upon them to be properly oiled and removed, for the purpose of cleaning them when the oil becomes gummed upon them, without disturbing other parts of the valve-gear.

To this end it consists in a novel construction of the yoke and of the valve-arm, and a novel arrangement of anti-friction rollers on the said arm, as hereinafter described, whereby the above objection is overcome.

In the accompanying drawings, Figure 1 represents a longitudinal section of a portion of a steam-pump embodying our invention, and Fig. 2 represents a transverse section upon the dotted line $x x$, Fig. 1, of the piston-rod and the valve-rod and its yoke, and an elevation of the piston-rod arm.

Similar letters of reference designate corresponding parts in both figures.

A designates the head and a portion of the steam-cylinder of the steam-pump, and B des-

ignates the head of the water-cylinder, which is connected with the steam-cylinder by a trunk, C, in the usual way.

D designates the piston-rod, to which the steam and water pistons are attached, and E represents a portion of an auxiliary valve and steam-chest, which may be of any desired construction, and the frame of which receives an oscillation or partial turning from the valve-rod F, which is guided in a standard, G, projecting from the water cylinder.

H designates a vertical arm, which may be rigidly secured to the piston-rod D in the desired position by means of a set-screw, a, or otherwise, and which has near its upper end an eye, b, through which the valve-rod F is inserted.

I designates a yoke, having lugs c at each end, which are fitted to the valve-rod, and after said yoke has been adjusted into the desired position on the rod it may be rigidly secured thereto by means of set-screws d in the lugs c, or otherwise. The yoke I is slotted for the greater part of its length, and the top of the arm H projects upward through and above said yoke and can reciprocate freely therein. Upon the top of the yoke I are two inclines, e, the one on one side being near one end of the yoke, and the one on the other side being near the other end of the yoke.

Through the arm H, above the valve-rod F, is inserted a transverse pin, f, and upon said pin, on each side of the arm, are loosely fitted rollers g, which are free to rotate, and which are immediately above the two sides of the yoke. As the piston-rod and its attached arm H are reciprocated the rollers g come alternately in position to, and do bear upon, the inclines e, thus turning or oscillating the yoke in one direction or the other, in accordance with the direction in which the arm is moving, and thus effect the desired turning or oscillation of the valve E.

The rollers g constitute, in effect, projections on the arm H on changing the sides of the yoke; but the rollers are preferable to rigid projections, because they lessen the friction upon the inclines e.

By our invention the cutting or excessive wear of the yoke and the arm which actuates it are obviated, and the desired motion is trans-

transmitted to the valve-rod in an easy and positive manner.

Our improved construction is advantageous for other reasons. The inclines upon the yoke 5 are in a plane which is approximately horizontal, only varying slightly therefrom at any time, and hence oil which is applied to the inclines will remain upon them and will not run off, as it would if the inclines were in planes approximately vertical.

Another advantage is that in case the rollers become gummed up with oil they may be readily removed for cleaning by simply taking out the screws which retain them in place, and 15 without disturbing other parts of the valve-gear. Another advantage is that any transverse strain exerted upon the yoke, and through it upon the valve-rod, is in the direction of the length 20 of the arm H, and is therefore transmitted to the piston-rod, which, being of large size, will not be affected by such strain.

We are aware that a valve-gear has been made in which the valve-rod has a slotted yoke arranged below and attached to it, and is oscillated by an arm projecting from the piston-rod and working in the slot in said yoke, said 25 arm being provided with a friction-roller for bearing on the yoke. We do not therefore claim this as of our invention. 30 What we claim as our invention, and desire to secure by Letters Patent, is—

1. In a direct-acting engine, the combination,

with the piston-rod and a valve and rod adapted to be oscillated or turned, of a yoke attached to the valve-rod and having inclines 35 upon opposite sides, and an arm projecting from said piston-rod and having horizontal projections upon opposite sides above the center of the valve-rod, the under sides of which are adapted to act upon the inclines on said yoke, 40 substantially as and for the purpose specified.

2. In a direct-acting engine, the combination, with the piston-rod and a valve and rod adapted to be oscillated or turned, of a yoke attached to said rod and having inclines on its upper 45 surface, and an arm projecting from said piston through and above said yoke, and provided with horizontal projections on opposite sides and above the center of the valve-rod, which overhang the sides of the yoke and are adapted to act upon the inclines thereon, substantially 50 as and for the purpose specified.

3. In a direct-acting engine, the combination of the piston-rod D, the valve E, the rod F, the yoke I, having inclines e e, and the arm H, 55 projecting through said yoke, and provided above the sides of said yoke and above the center of the valve-rod with the transverse pins f and rollers g, substantially as specified.

GEO. H. REYNOLDS.
